TEMPERATURE REGULATOR

Dexter Simpson, Knoxville, Tenn., assignor to
 The Fulton Sylphon Company, Knoxville,
 Tenn., a corporation of Delaware

Application June 7, 1935, Serial No. 25,492

5 Claims. (Cl. 236—34)

This invention relates to temperature regulators, and more particularly to a temperature regulator for controlling the circulation of the cooling medium through the cooling system of an internal combustion engine.

It is an object of this invention to provide a device of the type characterized which is simple in construction and which may be inexpensively manufactured by simple fabricating operations with the production of a minimum of scrap material.

A further object of this invention is to provide a device of the type characterized which is particularly adapted for large scale production, as for use in the water line of an automobile cooling system.

Other objects will appear as the description of the invention proceeds.

The invention is capable of receiving a variety of mechanical expressions, one of which is shown on the accompanying drawing, but it is to be expressly understood that the drawing is for purposes of illustration only and is not to be construed as a definition of the limits of the invention, reference being had to the appended claims for that purpose.

Referring to the drawing in detail, wherein the same reference characters are employed to designate corresponding parts in the several figures,

Fig. 1 is a perspective elevation, partly broken away, of an embodiment of the present invention;

Fig. 2 is a section on the line 2—2 of Fig. 1;

Fig. 3 is a central axial section through said embodiment.

As shown, the regulator takes the form of a substantially cylindrical casing 8 in which is suitably mounted a thermostat 9 operatively connected to a valve 10 for controlling the flow of cooling medium through said casing, which is designed to be mounted in any suitable water line, as for example, the hose line of an automobile cooling system. Said casing may be formed of any suitable material and in any suitable way, but for simplicity of construction it is preferably formed as a tubular wall open at opposite ends and conveniently formed by cutting sections from a tube or by drawing a sheet metal cup from a disk of sheet metal and cutting the bottom from said cup. Adjacent one end of the tubular wall 8, said wall is preferably beaded in any suitable way, as shown at 11, to provide an internal ledge 12, and a bead 13 may also be

formed at one end to facilitate retention of the casing in position as when a hose clamp is used.

Mounted on the said ledge 12 is an annulus 14 which may be secured to the ledge in any suitable way, as by indenting the tubular wall at a plurality of points 15 around the circumference so that the protuberances thereby formed at the inner face of the tubular wall will lock said annulus 14 against the ledge 12. The annulus 13 has a central aperture which constitutes a valve port, and cooperating with said port is the valve member 10 which preferably takes the form of a stamped disk shown as somewhat dished and also shown as substantially fitting said aperture. Valve member 10 is secured to a valve stem 17 in any suitable way, as by providing the outer end of said stem with a reduced portion 18 which receives the central aperture of the valve member 10, after which the end of the stem 17 may be peened or swaged over so as to lock the valve disk against the shoulder 19 at the inner end of said reduced portion. Valve stem 17 is preferably made hollow so that it may be used as a filling tube for the thermostat to be described, and the outer end of said aperture may be sealed in any suitable way, as by a ball 20 and a plug of solder 21.

The inner end of the valve stem is attached in any suitable way to the movable end wall 22 of the thermostat 9, which may be of any suitable construction here shown as in the form of an expandable and collapsible vessel having a lateral deeply corrugated wall 23. Said corrugated wall 23, at its opposite end, has integrally formed therewith or suitably attached thereto a cup-shaped end wall 24. As here illustrated, the end walls 22 and 24 are made separate from the corrugated lateral wall 23 and suitably attached to end corrugations thereof as by soldering, but if preferred, one of said end walls may be integral with the corrugated wall.

To mount end wall 24 stationarily in position, the opposite sides of the tubular wall 8 are provided with circumferential cuts 25 parallel to the end of the tube and at a distance therefrom approximating the axial length of the cupped projection on the end wall 24. Said cuts may extend for any suitable extent of the circumference of the tubular wall 8, say approximately 120° of the circumference. The two narrow strips 26 thus provided at the opposite sides of the tubular wall 8 and which are thus integrally connected with the tubular wall at their extremities but severed therefrom along their lengths, are then bent inwardly as shown in Fig. 1, and

provided with arcuate portions 27 midway of their lengths having a curvature such as to grip the cupped projection 24 between them. Thus, said strips 28 clamp the cupped projection 24 of the thermostat in position, and they may then be suitably attached thereto, as by soldering, so as to fixedly secure the thermostat against displacement. In place of embracing the cupped projection on said end wall the strips 28 could be formed to embrace any other suitable projection on the thermostat.

Intermediate the length of the tubular wall 8, said wall is provided with a pair of cuts 28 so as to provide a pair of oppositely disposed strips 28 which are integral with the tube at their extremities but severed from the tubular wall along their lengths. These cuts may be of substantially the same length as the cuts for forming the strips 28. Said opposed strips 28 are bent inwardly as shown in Fig. 2, and provided with arcuate portions 30 midway of their lengths of substantially the curvature of the stem 17 so as to provide a guide therefor.

Thereby the thermostat is fixedly secured in the tubular wall 8 and the valve stem 17 is provided with a guide which assures that said stem shall move rectilinearly with respect to the axis of said wall by merely providing saw cuts in said tubular wall and bending inwardly the strips so formed.

Valve member 10 may be provided with a leakage aperture 31 so that when the valve member is on its seat a small but predetermined circulation of water will occur to prevent the water around the thermostat being stagnant. The thermostat is preferably charged at a pressure below atmospheric so that at normal temperatures the valve is held against its seat by atmospheric pressure acting on the movable end wall of said thermostat, but if the thermostat leaks and becomes inoperative so that the internal pressure becomes equalized with the external pressure, the expandible and collapsible wall 23 will expand under its own resiliency, or the action of a spring if preferred, to lift the valve member 10 off of its seat and maintain a circulation through the tubular casing 8 to prevent overheating.

It will therefore be perceived that by the present invention a temperature regulator has been provided which is very simple in construction and which may be manufactured inexpensively because all of the fabricating operations are simple in character. The casing 10 may be cut from a continuous tube or drawn as a cup and the bottom removed therefrom. In the latter event, either the annulus 13 or the valve disk 16 or both may be cut from the disk so removed from the bottom of the cup to reduce the amount of scrap metal. The bead which forms the ledge 12 may be simply formed, and the annulus 13 may be secured thereto by a plurality of prick-punch indentations as described. The tube may be provided with a plurality of saw-cuts which form the strips 26 and 28, and said strips may be readily pressed inwardly and shaped so as to form a clamp for the cupped projection at the end of the thermostat and a guide for the valve stem. The thermostat, valve stem and valve disk

are also formed and secured together by simple operations, and therefore the entire device may be manufactured at low cost by simple and rapid operations.

While the embodiment of the invention illustrated on the drawing has been described with considerable particularity, it is to be expressly understood that the invention is not restricted thereto, as the same is capable of receiving other expressions, as will now be apparent to those skilled in the art, while changes may be made in the details of construction, arrangement and proportion of the parts without departing from the spirit of this invention. Reference is therefore to be had to the appended claims for definitions of the limits thereof.

What is claimed is:—

1. In a device of the character described, the combination of a tubular sheet metal casing, means in said casing providing a valve seat, a valve member cooperating with said seat, a valve stem connected to said valve member, a thermostat connected to said valve stem, and strips integral with and bent inwardly from said casing for mounting said thermostat in said casing.

2. In a device of the character described, the combination of a tubular sheet metal casing, means in said casing providing a valve seat, a valve member cooperating with said seat, a valve stem connected to said valve member, a thermostat connected to said valve stem, means mounting said thermostat in said casing, and strips integral with and bent inwardly from said casing forming a guide for said valve stem.

3. In a device of the character described, the combination of a tubular sheet metal casing, means in said casing providing a valve seat, a valve member cooperating with said seat, a valve stem connected to said valve member, a thermostat connected to said valve stem, said thermostat having a projection at one end thereof, and means for mounting said thermostat in position comprising strips cut from the wall of said casing and bent into clamping relation with said projection.

4. In a device of the character described, the combination of a tubular sheet metal casing, means in said casing providing a valve seat, a valve member cooperating with said seat, a valve stem connected to said valve member, a thermostat connected to said valve stem, means mounting said thermostat in said casing, and means for guiding said valve stem including strips cut from the wall of said casing and bent into embracing relationship to said stem.

5. In a device of the character described, the combination of a tubular sheet metal casing having a bead to provide an internal ledge, a ring secured on said ledge by indentations in said tubular wall and providing a valve seat, a sheet metal disk providing a valve member and substantially fitting the aperture in said ring, said valve member cooperating with said valve seat, a valve stem connected to said valve member, a thermostat connected to said valve stem, and means securing said thermostat in said casing.

DEXTER SIMPSON.
